UNITED STATES PATENT OFFICE.

DANIEL H. HARDEN, OF BANKS, ALABAMA.

BACK-BAND.

1,210,796.

Specification of Letters Patent.

Patented Jan. 2, 1917.

Application filed November 23, 1914, Serial No. 873,595. Renewed June 12, 1916. Serial No. 103,338.

To all whom it may concern:

Be it known that I, DANIEL H. HARDEN, a citizen of the United States, residing at Banks, in the county of Pike, State of Alabama, have invented certain new and useful Improvements in Back-Bands; and I do hereby declare the following to be a full, clear, and exact description of the invention, such as will enable others skilled in the art 10 to which it appertains to make and use the same.

This invention relates to improvements in harness and particularly to back bands.

One object of the invention is to provide a 15 novel device of this character which will readily conform to a large extent to the horse's back.

Another object is to provide a device of 20 this character which is simple in construction, and which can be readily manipulated and consequently repaired at a comparatively low cost.

Other objects and advantages will be apparent from the following description when 25 taken in connection with the accompanying drawings.

In the drawings: Figure 1 is a front elevation of a band made in accordance with my invention, Fig. 2 is a side elevation, Fig. 30 3 is a top plan view, and Fig. 4 is a longitudinal sectional view on the line 4—4 of Fig. 3.

Referring particularly to the accompanying drawings, 10, 11, 12 and 13 represent respectively a plurality of elongated rust 35 proof plates suitably hinged together as at 14. Suitably secured to the under sides of the plates and extending the full length of the series is a batting 15. Secured to each of the members 10 and 13 adjacent their inner ends are the tubular guys or terrets 16. Secured to the outer ends of the plates 10 and 13 are upwardly directed hooks 17.

By providing a plurality of hinged plates, the device will more readily conform 45 to the curvature of the horse's back, while the batting effectively protects the horse's back from rubbing.

What is claimed is:

A back band comprising a plurality of 50 pairs of hingedly connected plates, the upper plates of each pair being pivotally connected, a strip of batting contacting with and common to said plates, and means for connecting the batting to the plates adjacent their hinged connections.

In testimony whereof, I affix my signature, in the presence of two witnesses.

DANIEL H. HARDEN.

Witnesses:

N. C. GREEN,
L. S. CARONA.
